No. 705,969.

Patented July 29, 1902.

W. E. ROYS.

STEAM HEATING SYSTEM.

(Application filed Nov. 16, 1900.)

(No Model.)

UNITED STATES PATENT OFFICE.

WILLIS E. ROYS, OF RICHMOND HILL, NEW YORK, ASSIGNOR TO MARGARET T. ROYS, OF NEW YORK, N. Y.

STEAM-HEATING SYSTEM.

SPECIFICATION forming part of Letters Patent No. 705,969, dated July 29, 1902.

Application filed November 16, 1900. Serial No. 36,685. (No model.)

To all whom it may concern:

Be it known that I, WILLIS E. ROYS, a citizen of the United States, and a resident of the city of New York, borough of Queens, in the 5 county of Queens and State of New York, have invented a new and Improved Steam-Heating System, of which the following is a full, clear, and exact description.

The invention relates to gravity steam- 10 heating systems; and its object is to provide a new and improved steam-heating system whereby the user can control the amount of heat radiating from any radiator in the system to insure proper heating of rooms to a 15 predetermined degree and to provide a free return of the water of condensation to the steam-generator.

The invention consists of novel features and parts and combinations of the same, as 20 will be fully described hereinafter and then pointed out in the claim.

A practical embodiment of the invention is represented in the accompanying drawings, forming a part of this specification, in which 25 similar characters of reference indicate corresponding parts in all the views.

Figure 1 is a side elevation of the improvement. Fig. 2 is an enlarged sectional side elevation of the steam-trap for preventing 30 escape of steam from a radiator and allowing the return-flow of the water of condensation, and Fig. 3 is a sectional side elevation of the automatic return-trap for returning the wa- 35 ter of condensation to the steam-generator.

In gravity steam-heating systems of the double or single pipe types and as heretofore constructed it was necessary for the proper workings of the system to keep the radiator-supply valves completely open, as otherwise 40 the radiators would fill up in a short time with the water of condensation. This water of condensation should be returned to the steam-generator as quickly as possible to avoid undue exposure of the crown-sheet and 45 other exposed heating-surfaces. When the radiator is once filled with water and it becomes necessary to reopen the radiator-supply valve to again heat a room, then the wa- 50 ter in passing from the radiator and meet-

ing the hot steam in the pipes below produces 50 the well-known and undesirable pounding or hammering. Thus in systems of gravity steam-heating as heretofore constructed it was absolutely necessary to keep the radiator-supply valve fully open during the working 55 of the system to avoid serious consequences.

With my improved gravity steam-heating system the user can set the radiator-supply valve at any desired position to fill the radiator with more or less steam and heat the 60 room to a predetermined degree without danger of the water of condensation accumulat- 65 ing in the radiator and depriving the generator of the water or causing the undesirable pounding or hammering.

From a steam-generator A, of any approved construction, leads a steam-supply pipe B, connected by a branch pipe C with a radi- 70 ator D, of any approved construction, lo- 75 cated in the room to be heated. In the branch pipe C, adjacent to the radiator D, is arranged a radiator-supply valve E, of any approved construction and under the control of the operator to admit more or less steam to the radiator, as desired. The outlet of 75 the radiator is connected with a steam-trap F (shown in detail in Fig. 2) and connected by a return-pipe G with a pressure-relief de- 80 vice H, such as a receiver in the form of an open pipe, tank, or the like, so that the wa- 85 ter of condensation flows by its own gravity from the steam-trap F to the pressure-relief device H, which is open to the atmosphere. The pressure-relief device H feeds the water of condensation to an automatic return de- 85 vice I, connected with the generator A, so that the water of condensation is automatic- 90 ally returned to the generator without any back pressure being possible in the return- 90 pipe G.

The trap F consists, essentially, of a casing F', into which flows the water of condensation from the radiator D, and in the casing is ar- 95 ranged a float F², rising and falling with the water of condensation and preferably piv- 95 oted at F³ on a bracket F⁴, attached to the valve-seat F⁵, on which is adapted to be seated a valve F⁶, carried by the float F². The valve-

seat F⁵ connects with the return-pipe G, so that when the float F² swings upward the valve F⁶ moves from the valve-seat F⁵ and the water of condensation in the casing F' 5 can flow from the latter through the valve-seat F⁵ to the return-pipe G. The float F² and the valve F⁶ are so arranged that the valve F⁶ closes or seats itself on the valve-seat F⁵ previously to the valve-seat becoming 10 uncovered by the water in the casing F'. Thus by the arrangement described the water of condensation is freely discharged through the pipe G and flows by its own gravity to the pressure-relief device H, and at the same 15 time the steam in the radiator cannot escape into the return-pipe G, as the inlet thereto is sealed by the water in the trap when the valve F⁶ is open.

The automatic return device I (shown in 20 detail in Fig. 3) consists, essentially, of a casing I', connected by a pipe I² with the steam-compartment of the generator A, and on said pipe within the casing I' is arranged a valve I³, controlled by a float I⁴, rising and 25 falling with the water flowing into the casing I from the pressure-relief device H. A pipe I⁵ connects for the purpose the pressure-relief device H with the bottom of the casing I', and in this pipe I⁶ is arranged a check- 30 valve I⁶, which closes to the pressure-relief device H when the valve I³ is opened and steam passes into the casing I' and presses on the water therein. The water-return pipe I⁷, leading to the water-compartment of the 35 steam-generator A, is likewise connected with the casing I' and contains a check-valve I⁸, which closes when the valve I³ is closed by back pressure from the steam-generator on the water in the pipe I⁷. It is understood 40 that when the valve I³ is closed the float I⁴ is in a lowermost position, and water can now flow from the pressure-relief device H by its own gravity past the check-valve I⁶ into the casing I'. As the water rises the float I⁴ is 45 moved upward and the valve I³ is opened, so that the steam from the generator A passes into the casing I' and forces the water therein out through the pipe I⁷ past the check-valve I⁸ back into the generator A. During this 50 operation the check-valve I⁶ is closed to prevent a return flow of the water from the casing I' to the pressure-relief device H.

The main supply-pipe B is provided with the usual drip-pipe J for carrying the water 55 of condensation in the supply-pipe B back to the steam-generator. The radiator D is provided with a suitable air-valve K for letting out the air from the radiator when starting the system upon opening the valve E.

60 When the system is in operation, the valve E controls the amount of steam flowing into a radiator D to heat a room to a predetermined degree, the valve E being set correspondingly for the purpose—that is, opened more or less, 65 as the case may be. Now as the water of condensation in the radiator is immediately

disposed of by being caused to flow to the pressure-relief device H and as steam cannot escape into the return-pipe G it is evident that the radiator can be filled with any desired amount of steam to heat the room to that degree of heat to which the valve E is set. As the relief-pressure device H is at all times open to the atmosphere, it is evident that no back pressure whatever can act on the water in the return-pipe G or on the steam in the radiator D, and consequently my system will always be in proper working order, no matter to what position the said valve E is set. 75

80 From the foregoing it will be seen that the radiators in the different rooms of a dwelling, for instance, can be set independently one of the other, according to the degree of heat desired in any one of the rooms. Thus one room 85 may be highly heated, another moderately heated, and in a third one the heat may be entirely shut off without the slightest danger of causing hammering or pounding in the heating system. By the employment of the 90 traps F the steam is prevented from passing from one radiator by way of the return-pipe G to another radiator, and by having the return-pipe G open to the atmosphere there is no chance for binding air in the return-pipe, 95 and thereby causing back pressure therein and on the water of condensation in the trap, it being evident that with the controlling device E of a radiator partly opened and back pressure in the trap the water of condensation would be prevented from leaving the 100 radiator and the latter thus rendered uncontrollable. As the water of condensation is periodically, independently, and quickly returned from the several radiators to the boiler, 105 there is no danger from undue exposure of the crown-sheets and other exposed heating-surfaces, and at the same time the heat units of the water of condensation are not wasted, thus making the system not only a safe one, 110 but a very economic one.

Having thus fully described my invention, I claim as new and desire to secure by Letters Patent—

A gravity steam system, comprising a steam-generator, a plurality of radiators, steam-supply connections between the generator and the said radiators, steam-admission and temperature-controlling devices in the said connections adjacent to the radiators, each controlling device serving to regulate the amount of steam passing to its particular radiator and to control the degree of heat to which the room is to be heated, a water-of-condensation-disposing device connected with each radiator 115 and arranged to receive and discharge the accumulating water of condensation from the radiator independently of said controlling device and irrespective of the pressure in the radiator, said water-of-condensation-disposing device preventing escape of steam from 120 the radiator and a return connection between 125 the radiator and the water-of-condensation-disposing device connected with each radiator 130

the said water-of-condensation-disposing device and the said generator, to return the water of condensation to the generator, said return connection containing a pressure-relief device open to the atmosphere, and an automatic return device between the said generator and the said relief device, as set forth.

In testimony whereof I have signed my name to this instrument in the presence of two subscribing witnesses.

WILLIS E. ROYS.
